UNITED STATES PATENT OFFICE.

CHARLES S. MARSH, OF WINCHESTER, MASSACHUSETTS.

DECORATED COIN-HOLDER.

No. 811,509.

Specification of Letters Patent.

Patented Feb. 2, 1909.

Application filed November 11, 1907. Serial No. 401,617.

To all whom it may concern:

Be it known that I, CHARLES S. MARSH, of Winchester, county of Middlesex, State of Massachusetts, have invented an Improvement in Decorated Coin-Holders, of which the following is a specification.

In Letters Patent No. 862,984, dated August 13, 1907, granted to me, a coin-holder is shown adapted to contain two piles of coins, 10 the endmost coins of the piles being more or less exposed and in position to be engaged at the opposite ends of the device by the thumb and pushed outward through discharge slots provided for the purpose.

15 The device comprises essentially a cylindrical barrel having its ends more or less closed and formed with thumb-receiving recesses and discharge slots.

This device may be used as a souvenir and 20 for advertising purposes as well as put to many other uses when provided with a covering on the barrel having a picture or advertising matter or other decoration thereon.

This invention has for its object to improve 25 the construction of the device to the end that a decorated covering may be provided on the barrel. When applying such a covering to the barrel said covering must be held tightly on the barrel, it must not be 30 movable endwise thereon; it must be prevented from slipping off of the barrel by an endwise movement. It must be protected, particularly at the ends, against wear as the device is carried about while in the pocket, 35 and otherwise used. It must be prevented from coming in contact with the decorated covering of contiguous devices when packed in boxes for shipment and from engaging the sides of the box; or if packed in separate 40 boxes from engaging the sides of the boxes in which they are packed. It must be prevented from engaging a flat surface when the device is laid thereon.

In accordance with this invention the cylindrical barrel is provided with end caps, 45 which are made independent thereof and which are adapted to be driven onto or otherwise secured to the ends of the barrel, and said end caps are each formed with a thumb-receiving recess and with a discharge slot, and the internal diameters of said end caps correspond to the external diameter of the barrel so that the end caps extend outward beyond the external surface of the barrel for a short distance and the thickness of

the engaging walls of said end caps is greater than the thickness of the decorated covering which is applied to the barrel. The end caps thus extend peripherally beyond the decorated cover and thereby protect the same. 60

Figure 1 shows in perspective a coin-holder embodying this invention, the covering on the barrel being partially broken away and the barrel being partially broken away. Fig. 2 is a view of one end of the barrel.

a represents the cylindrical barrel which may be made of a piece of flat sheet metal bent into cylindrical form, or it may be otherwise formed. Each end of the barrel is formed with two notches *a'*, *a''*, arranged at opposite sides thereof. 70

b and *c* represent the end caps which are secured to the opposite ends of the barrel. 75 Each end cap is formed at its end with a thumb-receiving recess *b'*, *c'*, which extends down a short distance into its side wall, and is also provided with a discharge slot *b''*, *c''* arranged in its side wall. The internal diameter of each end cap corresponds to the external diameter of the barrel, so that it may be driven onto the end of the barrel and held tightly thereon, or it may be otherwise secured thereto. The end caps are 80 driven onto the barrel until the ends of the barrel engage the ends of the end caps, and when thus assembled one of the notches in the end of the barrel occupies a position opposite the thumb-receiving recess and the other notch occupies a position opposite the discharge slot. The engaging wall of each end cap is made of a substantial thickness to extend outwardly from the barrel a substantial distance. 85

d represents a covering which is applied to the barrel. This covering is made of any suitable material in sheet form or otherwise, and bent around, or otherwise applied to the barrel, its ends overlapping or abutting. This cover is made much thinner than the engaging walls of the end caps so that when the device is placed on a flat surface it will be supported by said end caps and the covering will be free from contact with the flat surface on which the device is laid. These end caps prevent any endwise movement of the covering and also protect the ends of the covering from wear while the device is being carried about in the pocket. 95 100 105 110

My invention is intended to include any kind of a decorated covering which is applied to the barrel and which it is desirable to protect and which will be protected by 5 the end caps constructed substantially as herein shown and described. Within the barrel and at each end thereof a circular plate *e* is placed and between said plates a spiral spring *f* is placed which acts to thrust 10 the circular plates toward the end caps, and upon each plate a pile of coins is placed and by the action of the spring said piles of coins will be thrust toward the end caps until the 15 endmost coins of the piles rest against the end caps and occupy positions opposite the discharge slots in the engaging walls thereof.

Having thus described my invention, what

I claim as new and desire to secure by Letters Patent is:—

A coin holder consisting of a barrel having end caps on its ends and a decorated sheet bent around said barrel and secured thereto, its opposite ends abutting against said end caps, said end caps extending peripherally beyond the sheet to protect the 20 25 same, substantially as described.

In testimony whereof, I have signed my name to this specification, in the presence of two subscribing witnesses.

CHARLES S. MARSH.
